INTERLOCKING METAL FLASHING

Filed Nov. 30, 1927

Inventor:
Allan Cheney.
by his atty. Charles S. Gooding.

UNITED STATES PATENT OFFICE.

ALLAN CHENEY, OF MELROSE, MASSACHUSETTS, ASSIGNOR TO THE CHENEY COMPANY, OF WINCHESTER, MASSACHUSETTS, A CORPORATION OF MASSACHUSETTS.

INTERLOCKING METAL FLASHING.

Application filed November 30, 1927. Serial No. 236,725.

This invention relates to improvements in building construction and particularly to an interlocking metal flashing which may be employed as a waterproof cut-off course between 5 courses of masonry.

The object of the invention is to provide a flashing, preferably constructed of sheet metal and pressed into such a form that when it is interposed between two courses of masonry 10 in conjunction with the usual layer of mortar, which is employed as a binding agent, that a perfect mechanical bond will be provided in every direction between the flashing and the adjacent courses of masonry.

15 The invention consists in an improved form of building construction and flashing as set forth in the following specifications and particularly as pointed out in the claims thereof.

20 Referring to the drawings:

Figure 1 represents a plan view of a portion of a strip of flashing embodying my invention.

25 Fig. 2 represents an edge view of the flashing.

Fig. 3 is an enlarged vertical section through the wall of a building illustrating my improved flashing inserted between 30 courses of masonry at several locations upon said wall.

Fig. 4 is an enlarged sectional view taken longitudinally of the strip of flashing at a position as indicated by the lines 4-4 of Fig. 3.

35 Fig. 5 is a plan view illustrating a modified embodiment of my invention.

Like numerals refer to like parts throughout the several views of the drawings.

In the drawings, referring particularly to 40 Figs. 1 to 4 inclusive, 5 represents a strip of flashing preferably constructed of sheet metal and folded to provide grooves 6 and ridges 7 alternately arranged upon both sides of the strip. The grooves and ridges are furthermore formed with side walls 8 which are common to both the grooves and the ridges and said walls are inclined to both of the faces of the flashing material in a manner to form dove-tail shaped grooves and ridges. The side walls 8, furthermore, of both grooves and ridges taper longitudinally of said grooves and ridges toward an edge of the material, and preferably, the opposite sides of a groove on one face of the strip tapers in the opposite

direction to that in which the opposite sides 55 of the adjacent groove which is located upon the same face of the strip tapers.

The strip 5 of flashing is slightly less in width than the width of the wall in which it is employed, and said strip is embedded in the 60 mortar which is used as a binding agent for the courses of masonry which are located immediately above and below the strip.

In Fig. 3 I have illustrated a conventional form of wall in which strips of flashing embodying my invention are inserted at A, B and C. The wall illustrated in Fig. 3 embodies therein a coping 9, a plurality of courses of brick 10, a flashing block 11 and a cornice 12, all of which are joined together 70 in a well-known manner by layers of mortar 13.

When utilized at either of the locations A, B or C the strip of flashing 5 will form a waterproof cut-off course between the 75 course of masonry located thereabove and therebelow, and said strip of flashing will prevent water, which may have found its way between the courses of masonry located thereabove, from seeping downwardly into 80 the courses of masonry located therebeneath. Especially will the strip of flashing located at B prevent water from above from seeping downwardly between the courses of masonry located therebelow and from getting beneath 85 the flashing material 14, which is provided for the protection of the roof 15.

By providing the alternate grooves 6 and ridges 7 and by tapering said grooves and ridges as illustrated, it is possible to embed 90 the strip of flashing in the mortar 13 between the two courses of masonry and provide a perfect bond between the flashing and the mortar upon each side thereof and also between the adjacent courses of masonry between 95 which the flashing strip is located.

At certain locations upon the wall, particularly at points below the roof, as for example, at C, it is desirable to have the flashing extend upwardly from the layer of mortar in which it is embedded against the inner surface of the wall, and this is accomplished by flattening the opposite ridges of the flashing and bending the strip longitudinally thereof to form an upwardly extending 100 flange c, and it will be evident that where a flange is so provided that if, by any chance, water enters the wall above this flashing strip 105

and seeps downwardly to the upper surface thereof, that it will be prevented from working inwardly beyond the flange *c* and doing damage upon the interior of the building.

5 In Fig. 5 I have illustrated a modified embodiment of my invention in which a strip of flashing 16 is folded to form alternately arranged grooves 17 and ridges 18, and as in the case of the strip of flashing 5 previously 10 described, side walls 19 of a groove on one face of the strip 16 tapers in the opposite direction to that in which the adjacent groove on the same face of the strip tapers. This 15 strip of flashing may be employed in exactly the same manner as is the strip 5, with exactly the same result being obtained.

I claim:

1. A flashing comprising a continuous strip 20 of sheet material, embodying therein a plurality of dove-tail shaped grooves and ridges, the opposite sides of a groove on one face of the material tapering longitudinally of the groove in the opposite direction to that

in which the opposite sides of another groove on the same face of the material tapers. 25

2. A building construction comprising superposed courses of masonry, a layer of binding material for said courses, and a section of sheet metal flashing embedded within said binding material, said section embodying therein a plurality of grooves and ridges each having sides inclined to the face of the material and also tapering longitudinally thereof in opposite directions on both sides thereof respectively, whereby the masonry is 30 35 bonded together in all directions.

3. A flashing sheet consisting of a continuous strip of sheet metal bent to form shallow dovetailed grooves on its opposite sides, the 40 grooves on each side having their alternate edges parallel and the remaining edges inclined alternately in opposite directions.

In testimony whereof I have hereunto set my hand.

ALLAN CHENEY.
